DESIGN FOR AN AUTOMOBILE REAR VIEW MIRROR AND SUPPORT THEREFOR

Rene Daon, Norwalk, Conn., assignor to Yankee
Metal Products Corp., Norwalk, Conn., a corpora-
tion of Connecticut

Application December 29, 1945, Serial No. 125,184

Term of patent 14 years

(Cl. D14—6)

To all whom it may concern:

Be it known that I, Rene Daon, a citizen of the United States, residing in Norwalk, county of Fairfield and State of Connecticut, have invented a new, original, and ornamental Design for an Automobile Rear View Mirror and Support Therefor, of which the following is a specification, reference being had to the accompanying drawings, forming part thereof.

Fig. 1 is a rear elevational view of an automobile rear view mirror and support therefor showing my new design; and

Fig. 2 is a side elevational view thereof.

The characteristic features of my design reside in the portions shown by means of full lines in the drawing.

I claim:

The ornamental design for an automobile rear view mirror and support therefor, as shown and described.

RENE DAON.
